(57) **CLAIM**

The ornamental design for a recycling receptacle, as shown and described.

DESCRIPTION

FIG. 1 is a perspective view of one embodiment of the recycling receptacle with the broken lines showing environmental association matter for illustrative purposes only and forming no part of the claimed design;

FIG. 2 is a top plan view thereof;

FIG. 3 is a side elevation view thereof;

FIG. 4 is a second side elevation view thereof;

FIG. 5 is another side elevation view showing that the sides of the invention are contiguous and uniform; and,

FIG. 6 is a bottom plan view.

1 Claim, 3 Drawing Sheets

FIG.3

FIG.4
